(57) **CLAIM**

What is claimed is the ornamental design for a modular tray set, as shown and described.

DESCRIPTION

FIG. 1 is a front perspective view of a tray design of a modular tray set design;

FIG. 2 is a top view of the tray design of the modular tray set design;

FIG. 3 is a bottom view of the tray design of the modular tray set design;

FIG. 4 is a front view of the tray design of the modular tray set design;

FIG. 5 is a right side view of the tray design of the modular tray set design;

FIG. 6 is a right side perspective view of a partition design of the modular tray set design;

FIG. 7 is a top view of the partition design of the modular tray set design;

FIG. 8 is a bottom view of the partition design of the modular tray set design;

FIG. 9 is a right side view of the partition design of the modular tray set design; and

FIG. 10 is a front view of the partition design of the modular tray set design; and,

FIG. 11 is a perspective view of the modular tray set shown with partition.

The phantom lines showing indicia on the front of the modular tray set are included for the purpose of illustrating portions of the modular tray set and form no part of the claimed design. The broken lines form no part of the claim.
